(57) **CLAIM**

I claim the ornamental design for a vehicle diagnostic tool, as shown and described.

DESCRIPTION

FIG. 1 is a front elevational view of a vehicle diagnostic tool showing my new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof from the front, to the left and above; and,

FIG. 8 is a second perspective view thereof from the back, to the right and below.

In the drawings, the broken lines are shown for illustrating portions of the vehicle diagnostic tool and form no part of the claimed design.
